UNITED STATES PATENT OFFICE.

BARNEY E. MCCOY AND KENNETH NASH, OF NEW HARMONY, INDIANA; SAID NASH
ASSIGNOR TO E. W. NASH, OF NEW HARMONY, INDIANA.

CORD-REEL FOR VEHICLE-LIGHTS.

1,125,858.

Specification of Letters Patent. Patented Jan. 19, 1915.

Application filed May 7, 1913. Serial No. 766,239.

To all whom it may concern:

Be it known that we, BARNEY E. McCoy and KENNETH NASH, citizens of the United States, residing at New Harmony, in the county of Posey and State of Indiana, have invented certain new and useful Improvements in Cord-Reels for Vehicle-Lights; and we do hereby declare the following to be a full, clear, and exact description of the invention, such as will enable others skilled in the art to which it appertains to make and use the same.

This invention relates to adjustable cord supports for electric lights and as its principal object aims to provide a cord reel constructed with such regard to proportion, number and arrangement of parts that it may be cheaply manufactured, will be durable and efficient in its operation, and may be quickly and easily repaired in the event that any of the working parts are damaged or broken.

A further object is to provide an adjustable cord reel for electric lights which may be readily attached to any convenient portion of an automobile, and will permit the operator of the machine to quickly inspect any punctured tires or damaged mechanism of the machine by merely pulling the light in the direction in which the damaged portion of the machine lies.

The above and additional objects are accomplished by such means as are illustrated in the accompanying drawings, described in the following specification and then more particularly pointed out in the claims which are appended hereto and form a part of this application.

With reference to the drawings, wherein we have illustrated the preferred embodiment of our invention as it is reduced to practice, and throughout the several views of which similar reference numerals designate corresponding parts: Figure 1 is a horizontal section through the reel. Fig. 2 is a vertical sectional view taken through the device as shown in Fig. 1 centrally thereof. Fig. 3 is a vertical sectional view taken centrally through the device as shown in Fig. 1, being a more detailed view than Fig. 2, and illustrating the contacts and brushes employed in the drum. Fig. 4 is an inner face view of the base block. Fig. 5 is a detail view illustrating in section the portion of the casing through which the cord plays. Fig. 6 is a detail view of the pawl and ratchet stop for the drum shaft.

Proceeding now to the description of the drawings, the numeral 1 designates the base block of the reel. This base block is preferably circular in shape and is provided adjacent its edge with the circumferentially spaced screw holes 2, adapted to receive bolts, screws, or other fastening devices for attaching the base to any portion of the body or running gear of the vehicle. 60

tive wires 22 and 23 to the binding posts 24 and 25, respectively. The binding post 22 is connected to the positive wire 26 of the batteries or magneto of the engine 27 through the binding post 28, shaft 7, and disk 17. The positive wire 29 is connected to the binding post 25 through the binding post 30 carried on the member 1 through a radial arm 32 fixed on the member 1 and 10 provided at its inner terminal with a circular contact ring 33 arranged on the member 1 concentrically with relation to the shaft 7. The hub 16 carries an insulated block 34 in which is mounted a spring 15 pressed brush or contact rod 35 adapted to contact with the ring 33 during the rotation of the hub. The binding post 25 is threaded through the insulating block 34 and contacts at its inner terminal with the stem 36 20 of the brush 35.

From the foregoing it will be apparent that when it is desired to unwind the cord it is only necessary to pull the lamp consequently rotating the hub 16 on the shaft 7 25 and thus unwinding the cord 20 against the tension of the spring 13. When the cord 20 has been drawn to the desired extended position the pawls 9 will engage the notches 19 and hold the hub 16 against further movement until the operator desired to rewind the cord 20, at which time it is only necessary to pull the cord 20 out a slight distance in a manner similar to the manipulation of the ordinary house shades and the spring 13 35 will rotate the hub 16, rewinding the cord.

It is desirable to emphasize the fact that this invention provides a comparatively simple cord reel which may be attached to any portion of the structure of an automobile or other vehicle, and permit the operator to have a handy light which may be readily extended from its support to permit the inspection of any broken or damaged portions of the vehicle.

45 In reduction to practice, we have found that the form of our invention, illustrated in the drawings and referred to in the above description, as the preferred embodiment, is the most efficient and practical; yet, realizing that the conditions concurrent with the adoption of my device will necessarily vary, we desire to emphasize the fact that various minor changes in details of construction, proportion and arrangement of parts may 50 be resorted to, when required, without sacrificing any of the advantages of our invention, as defined in the appended claims.

What is claimed is:

1. In a device of the character described 60 the combination with a base plate, and an electrical circuit of a cylindrical casing

mounted upon said base plate, a shaft secured centrally to said base plate and extending outwardly therefrom into the casing, a pair of annular disks mounted upon 65 said shaft within the casing in spaced relation to each other and to the base plate, laterally extending peripheral flanges formed on said disks and disposed in over-lapping engagement with each other so as to space 70 said disks and form a compartment, a coil spring secured at one terminal to the shaft within the compartment formed by the disks and at its other terminal to the disks, said disks being loosely mounted on said shaft 75 and adapted for rotation thereon, an annular disk loosely mounted on said shaft in spaced relation to the adjacent disk and to the base plate, a hub fixed to said last named annular disk and to the adjacent of the first 80 named annular disk centrally thereof, an electric light cord secured to said hub and adapted to be wound thereon, an electric lamp carried upon said cord and means for operatively connecting the lamp with said 85 electrical circuit.

2. In a device of the character described the combination with a base plate and an electrical circuit of a cylindrical casing secured thereto, a shaft secured centrally to 90 the base plate and extending into said casing, a pair of annular disks mounted loosely upon said shaft within the casing in spaced relation to each other, lateral annular flanges formed upon the peripheries of the disks and 95 secured to each other in overlapping position so that the disks form a compartment, a coil spring mounted within said compartment and secured terminally to the shaft and the disks disposed in spaced relation to 100 the base plate, an annular disk rotatably mounted upon said shaft in spaced relation to the innermost of the first named disks so as to form a light cord receiving compartment, a hub member connecting said last 105 named and one of the first named disks, a light cord secured to said hub member and adapted to be wound thereon, an electric light carried by said light cord, means for operatively connecting the light with said 110 electrical circuit carried by said last named disk and base plate and an inwardly extending annular flange formed on said casing and adapted for engagement with the outermost of said first named disks. 115

In testimony whereof we affix our signatures in presence of two witnesses.

BARNEY E. MCCOY.
KENNETH NASH.
